UNITED STATES PATENT OFFICE.

LE ROY HUTSON AND ALBERT SCHUPP, JR., OF HURLEYVILLE, NEW YORK.

DESIGN FOR A ROD FOR WINDOW-SHADE BRACKETS AND CURTAIN-POLE SUPPORTS.

SPECIFICATION forming part of Design No. 32,124, dated January 23, 1900.

Application filed December 7, 1899. Serial No. 739,581. Term of patent 14 years.

To all whom it may concern:

Be it known that we, LE ROY HUTSON and ALBERT SCHUPP, Jr., citizens of the United States, residing at Hurleyville, in the county of Sullivan and State of New York, have invented and produced a new and original Design for a Rod for a Window-Shade Bracket and Curtain-Pole Support; and we do hereby declare the following to be a full, clear, and exact description of the same, reference being had to the accompanying drawing, forming a part thereof.

In the accompanying drawing the figure is a perspective view of a rod for a window-shade bracket and curtain-pole support embodying our design.

The leading feature of our design consists of a vertical standard provided with approximately right-angular attaching-arms and a semicircular curtain-pole-supporting loop.

A in the drawing represents a vertical standard, which is provided with an approximately right-angular-shaped attaching-arm

a at its lower end and another approximately right-angular-shaped arm a^2 located near the upper end of said standard. The said standard is also provided at its upper end with a semicircular curtain-pole-supporting loop a^3 , which extends from the standard in an opposite direction from the outer end of the upper attaching-arm a^2 , but parallel therewith. The attaching-arms a and a^2 are provided with attaching-apertures a^4 .

Having now described our invention, what we claim, and desire to secure by Letters Patent of the United States, is—

The design for a rod for a window-shade bracket and curtain-pole support, substantially as herein shown and described.

In testimony whereof we hereunto affix our signatures in presence of two witnesses.

LE ROY HUTSON.
ALBERT SCHUPP, JR.
